Int. Cl. D6—04

U.S. Cl. D6—152

FIG. 1 is a perspective view of a chest of drawers or similar article, showing my new design; and

FIG. 2 is a side elevation view thereof.

This application is a division of my earlier filed case Ser. No. D. 23,579 filed June 22, 1970 and now Design Pat. No. D. 225,150.

I claim:

The ornamental design for a chest of drawers or similar article, substantially as shown and described.
